United States Patent

Des. 235,431
Patented June 17, 1975

235,431

MOTORCYCLE WHEEL

Delmer D. Scott, Encino, Calif., assignor to Shelby Dowd
Industries, Inc., Marina Del Rey, Calif.

Filed June 21, 1974, Ser. No. 483,936

Term of patent 14 years

Int. Cl. D12—16

U.S. Cl. D12—205

FIG. 2.

FIG. 3.

FIG. 1 is a front elevational view of a motorcycle wheel showing my new design, it being understood that the rear is a mirror image thereof;

FIG. 2 is a side elevational view thereof;

FIG. 3 is a cross-sectional view thereof taken on the line 3—3 in FIG. 1; and

FIG. 4 is a cross-sectional view of a spoke taken on the line 4—4 in FIG. 1.

I claim:

The ornamental design for a motorcycle wheel, as shown.
